WIPER HOLDER FOR PERFORATOR-CARD MACHINES

Cornelis Hendricus Stuivenberg, Haarlem,
NetherlandsApplication August 6, 1947, Serial No. 766,769
In the Netherlands August 27, 1945Section 1, Public Law 690, August 8, 1946
Patent expires August 27, 1965

10 Claims. (Cl. 235—61.11)

1

The present invention relates to perforator-card machines with electrical feeler or sensing arrangement in which the feelers or wipers consist of very fine metal wires similar to the hairs of a brush. In such machines, it is necessary frequently to check the feelers or sensing means and, to this extent, the feelers or sensing means, which are also called wipers, must be removed by dismounting the holder device for the feelers. In machines of the type involved, as heretofore known, the feeler holder can only be shifted within straight guides, while a locking device is provided for locking the feeler holder in its operative position. One of the drawbacks of the devices under consideration as heretofore known, consists in that, when the feelers are brought into their working position after a check-up, they are moved in the direction of their longitudinal axes. As a result thereof, the fine wires stab into or stick to the paper so that the fine wires are easily damaged, bent or otherwise harmfully affected. In order to avoid such damage, it was heretofore necessary to bring the feelers or wipers into their working position only when the machine is running, so that the wipers will meet a moving plane and therefore slip away when coming into contact with the working surface. Thus, a sticking or stabbing can be avoided if the wipers are carefully advanced into their working position. However, due to the fact that the machine must be operated while the insertion of the feelers or wipers is being effected, it was heretofore necessary to employ two persons, namely, one for operating the machine, and a second one for effecting the insertion of the wipers or feelers.

It is the primary object of the present invention to overcome this drawback, so as to allow the insertion of the feelers or wipers while the machine is at a standstill, thereby making the second person referred to above, superfluous.

It is another object of this invention to provide a wiper holder for perforator-card machines which is simple in construction and will automatically provide different paths for the wiper holder during its insertion into and removal from the respective card machines.

These and other objects and advantages of the invention will appear more clearly from the following specification in connection with the accompanying drawings, in which:

Figure 1 illustrates an embodiment of the wiper holder according to the present invention as seen in the moving direction of the cards, the wipers being in their operative position.

10

Figure 2 shows the left hand guide for the wiper holder seen from the center portion of the wiper holder.

Figure 3 illustrates the view of the wiper holder seen from the left hand side of Figure 1.

Figure 3A is a perspective view of the part illustrated in Figure 3.

Figure 4 is a perspective view of the guides shown in Figures 2 and 3.

Figure 4A illustrates on an enlarged scale a detail of Figure 4.

Figures 5 to 8 show various positions occurring while the wiper-holder is being inserted.

Figure 9 represents a section through the wiper-holder and the contact devices for supply of current to the wipers.

Figure 10 is a diagrammatic showing of the principles governing the construction of the guiding means in connection with the present invention.

General arrangement

As stated above, it was necessary with wiper-holders for perforator-card machines as heretofore known, to have one operator operate the machine while a second operator inserted the wiper-holder. In order to overcome the drawback of requiring two operators for this operation, and in order to simplify the entire inserting operation of the wiper-holders, the holding means for the metal wire wipers are, according to the present invention, supported in such a manner that different paths of movement of the holding means and thereby the wipers are provided for the insertion of the holding means into and the removal of the holding means from the supporting means for the holding means.

In order more clearly to bring out the idea underlying the present invention, reference may be had to Figure 10. In this figure, the wire wiper is designated by the reference numeral 1 and is shown in its working position. When this wiper is moved from the position 1a into the working position, no sticking or stabbing will occur, for the following reason: The path of the movement of the lower end of the wiper is designated s and may be split up into the component a and the component b. The component a represents a retracting movement of the wiper. It is clear that, if the component a would reverse its direction, a stabbing action of the wiper would be unavoidable.

For the discussion of the problem involved, the direction of the component a may be taken as being of negative value. The question in connection with the present problem is now,

55

how the movement has to be in order to cause the component a always to have the said negative value. It will be clear that such desired result can be obtained only when the active or lower end of the wiper moves along a path between the feeling surface and the plane at right angle to the axis of the wiper, said plane and feeling surface being clearly indicated in Figure 10. In other words, the path of movement must be within the angle α . It is, however, not necessary that this path of movement be straight. If the movement of the wiper-holder should be along a curved path, or should be a rotative movement, the location of the pivots about which such rotative movement takes place, must be within the angle β . This is due to the fact that the radius of rotation must be at right angles with regard to the required path of movement of the wiper.

Structural arrangement

Referring now to the specific structure shown in the drawings, by way of example, the reference numeral 1 represents a wiper-holder which has a left hand side plate 2 in right hand side plate 2a. Each side plate has been equipped with a relatively short cylindrical guiding-cam 3.

The side plate 2 furthermore comprises a guiding-cam 5 of a rectangular section, which cam has a greater length than cam 3. The side-plates 2 and 2a in image are equal to each other. Therefore the same reference-figures have been chosen as reference-marks for the right hand sideplate, only the affix "a" being added. For the sake of simplicity, only the left hand side of the wiper-holder will be discussed below. Attached to the side 6 of the machine are guiding parts 7 and 8, which together define a guiding track 9 for the cam 3 of the sideplate 2. A pawl 10 for locking the wiper-holder in its operating position is rotatable around a stud 11 and is acted upon by a spring 12. When the pawl 10 is in its operative position, the lower part thereof extends in front of the cam 3 (see Fig. 2) (in the other direction) to such an extent that cam 3 is firmly retained in the lower part of the guiding track 9. The upper part of the guiding track 9 is closed by a guiding device 13 fixed to a spring 14 that is so applied to the side 6, that the guiding device 13 can be pushed back in sideward direction (Fig. 1) against the thrust of spring 14. It stands to reason that the side 6 of the machine is provided with a corresponding notch through which the guiding device 13 can pass.

As regards its form, the guiding device 13 can best be seen in Fig. 4. It has a bevel surface 15 and a recess 16, which has the same dimensions as the cam 5 of the sideplate 2 and ends in a beveled surface 17. With reference to the beveled surface 15 it may be observed that its dimensions also correspond to those of the cam 5 of the sideplate 2 of the wiper-holder 1.

While the guiding track 9 is destined for the straight guiding of the cam 3 of the sideplate 2, the guiding device 13 serves to compel the cam 5 of the sideplate 2 to move in different directions when the wiper-holder is removed and re-inserted respectively.

When the wiper-holder is removed, it must be possible to move the cam 5 as well as the cam 3 in a straight direction, while during the insertion of the wiper-holder 1 the cam 5 knocks against the upper plane of the guiding device 13

13, thus preventing a further straight movement of the cam 5 (see Fig. 5).

In order to be able to bring the wiper-holder 1 into its operating position, the wiper-holder 1 must be revolved around the cams 3 and 3a in such a way that the cams 5 come sidelong of the guiding device 13 (see Fig. 6), in which position the wiper-holder can be moved in the direction of the contact-roll, till it arrives in the position shown in Fig. 7. In this position of the wiper-holder 1 the pawl 10 drops behind the cam 3 which latter has reached the lower part part of the guiding track 9, and thus prevents the wiper-holder 1 from being lifted out once more. Now it is only possible for the wiper-holder to be revolved around the cams 3 and 3a that have been locked by the pawls 10 and 10a.

In the position of the wiper-holder according to Fig. 7 the wipers are not yet resting against the contact roll. If, however, now the wiper-holder is revolved clockwise in the position represented in Fig. 8, then the wipers with the required tension are pressed against the contact roll. The cam 5 of the sideplate 2 co-operates with the beveled surface 15 of the guiding device 13 and against the thrust of spring 14 pushes this device back, whereupon the guiding device 13 under the influence of the spring 14 can again shoot forward when the cam 5 comes within the reach of the notch 16 of the guiding device 13. Now the cam 3 is in the notch 16 of the guiding device 13 and is locked by this device in the position according to Fig. 8.

If the wiper-holder 1 has to be removed from the machine, it is sufficient to release the pawls 10 and 10a and thus to release the cams 3 and 3a. Due to the tension of the wiper wires the whole wiper-holder 1 is pushed back over a small distance. During this movement, the cam 5 of the sideplate 2 co-operates with the beveled surface 17 of the guiding device 13, and the guiding device 13 is turned back over a short distance against the thrust of the spring 14. If now the wiper-holder 1 is seized and pulled back further, the guiding device 13 is pushed aside further by the cam 5; after having passed the cam 5, the device 13 shoots again into its locking position. So the wiper-holder 1 cannot be brought again into its operating position by simply pushing it in, since the guiding device 13 prevents the straight pushing in, as has been explained above. Since the cam 3 is shorter than the cam 5, it is not within the reach of the guiding device 13, so that, after the cam 5 has pushed the guiding device 13 aside in the manner described before, the wiper holder 1 can be pulled out without difficulties.

In another embodiment of the invention, the rotative movement of the wiper-holder can be utilized to effect the conducting connections between the wipers of the holder and the supply conductors. According to the invention the wiper-holder is provided with contacts that during the insertion of the wiper-holder co-operate with springing contact-devices in the machine in such a way that they effect the connection of the separate wipers with the additional supply conductors. The springing contacting devices are, preferably by guiding elements, prevented from sideward movements when the wiper-holder is being inserted or removed. This may be realized by equipping the wiper-holder contacts with a cut-out part, e. g. a groove, for

the dropping in of the corresponding springing contacting-device.

Fig. 9 shows contacts that have been arranged in three rows above each other and in a leaping manner towards each other; each of these contacts being connected conductively to a wiper. Each of the contacts 18 is co-operating with a springing contact tongue 19 that has been arranged stationarily in the machine, to which contact tongue the supply conductor to the wipers has been connected.

When the wiper-holder 1 is being inserted in the manner described above, the contacts 18 by the rotative movement of the wiper-holder 1 are pressed against the springing contact tongues 19 and thus the connections for the wipers are effected.

When the wiper-holder 1 is being removed, the contacts 18 shift relative to the contact tongues 19, owing to which the proper contact planes of both parts on account of the friction remain very clean and any dirt as e. g. dust is removed again.

The invention is in no respect restricted to the described embodiment. The essential part of the invention is only that the wiper-holder when being inserted or removed is moved in different routes in such a manner that the wiper wires only at the end of the insertion movement are subjected to a supplementary movement, in particular a turning movement of the wiper-holder.

For guiding the wiper-holder when it is being inserted or removed, also guiding devices other than those described before, can be used. It is in particular possible to use guiding tracks which have been equipped with guiding devices that function as change-over tongues to effect the changes of direction; dependent on the movement of the wiper-holder these change-over tongues always take the position appropriate to the opposite movement of the wiper-holder.

What I claim is:

1. For use in connection with feeler means comprising a metal wire wiper for analyzing record cards, an arrangement comprising in combination, holding means for holding said wiper, control means connected to spaced portions of said holding means, each of said control means being provided with a guiding member and with cam means spaced from said guiding member, supporting means arranged adjacent each of said control means for supporting said control means, said supporting means comprising means forming a straight path guiding track for said guiding member, and yieldable guiding means associated with said supporting means and arranged to cooperate with said control means for guiding said cam means respectively along a straight and a curved path during insertion of said holding means into and the removal of said holding means from said supporting means.

2. For use in connection with feeler means comprising a metal wire wiper for analyzing record cards, an arrangement comprising in combination, holding means for holding said wipers, control means connected to spaced portions of said holding means, each of said control means being provided with a first cam member and a second cam member spaced from said first cam member, supporting means arranged adjacent each of said control means for supporting the same, first guiding means rigidly connected to said supporting means for guiding said first cam member along a straight path, second guid-

ing means yieldingly connected to said supporting means for guiding said second cam member along a curved path during placement of said holding means into operative position, and means operable selectively to lock and unlock said first cam member for respectively allowing rotative movement only of said cam member or for allowing withdrawal of said holding means from said supporting means.

3. For use in connection with feeler means comprising a metal wire wiper for analyzing record cards, an arrangement comprising in combination, holding means for holding said wipers, control means connected to spaced portions of said holding means, each of said control means being provided with a first cam member and a second cam member spaced from said first cam member, supporting means arranged adjacent each of said control means for supporting the same, first guiding means rigidly connected to said supporting means for guiding said first cam member along a straight path during placement of said holding means into operative position and during removal of said holding means from said operative position, second guiding means having a plurality of separate guiding surfaces for respectively guiding said holding means along a predetermined first path during removal of said holding means from said operative position and for guiding said holding means along a second predetermined path during insertion of said holding means into operative position, yielding means connected to said supporting means and continuously urging said second guiding means into a predetermined position to cause the latter to prevent insertion of said holding means along the path of removal of said holding means, and locking means associated with said supporting means for automatically locking said first cam member so as to allow rotative movement of said control means only, said last-mentioned means being operable manually for making the same ineffective to thereby allow removal of said holding means.

4. For use in connection with feeler means comprising a metal wire wiper for analyzing record cards, an arrangement comprising in combination, holding means for holding said wipers, control means connected to spaced portions of said holding means, each of said control means being provided with a first cam member and a second cam member spaced from said first cam member, supporting means arranged adjacent each of said control means for supporting the same, first guiding means rigidly connected to said supporting means for guiding said first cam member along a straight path, second guiding means yieldingly connected to said supporting means for guiding said second cam member along a curved path during placement of said holding means into operative position, and contact means associated with said control means and operable in response to the placement of the wiper holder into its operative position for establishing electrical connection of said wipers with a current supply line.

5. For use in connection with feeler means comprising a metal wire wiper for analyzing record cards, an arrangement comprising in combination, holding means for holding said wipers, control means connected to spaced portions of said holding means, each of said control means being provided with a first cam member and a second cam member spaced from said first cam member, supporting means arranged ad-

jaçent each of said control means for supporting the same, first guiding means rigidly connected to said supporting means for guiding said first cam member along a straight path, second guiding means rigidly connected to said supporting means for guiding said second cam member along a curved path during placement of said holding means into operative position, yielding contactors associated with said holding means, contact elements associated with said control means for automatically contacting said contactors in response to the movement of said holding means into operative position, and means for preventing sideward movements of said yielding contactors during movement of said holding means into operative position.

6. A device for analyzing record cards comprising in combination, feeler means operable to engage and analyze said cards when moved thereover, said feeler means comprising a metal wire wiper for contacting the cards to be analyzed, a wiper holder for supporting said feeler means, pivot means for pivotally supporting said feeler means, a supporting device for movably supporting said wiper holder and guiding the same along a first path during movement of said wiper holder into operative position while guiding said wiper holder along a second path during removal of said wiper holder from operative position, the path of movement of the free end of said wiper when said wiper holder is being moved into working position lying within an acute angle defined between the plane of the card to be analyzed and the plane passing through the analyzing point of said wiper at the right angle to the axis of said wiper, and the path of movement of the free end of said wiper during removal of said wiper holder during its operative position being located within the angle supplemental to said acute angle, i. e., the obtuse angle between the said planes.

7. A device for analyzing record cards comprising in combination, feeler means operable to engage and analyze said cards when moved thereover, said feeler means comprising a metal wire wiper for contacting the cards to be analyzed, a wiper holder for supporting said feeler means, pivot means associated with said wiper holder, guiding means for guiding said pivot means, and means associated with said guiding means and operable to lock said pivot means so as to allow only rotative movement of said wiper holder, said last-mentioned means being operable in response to the movement of said pivot means into a position defined by a plane at a right angle to the longitudinal axis of said pivot means and located between a line passing through the analyzing point of said feeler means and at right angles to the analyzing plane and the axis of said feeler means.

8. A device for analyzing record cards comprising in combination, feeler means operable to engage and analyze said cards when moved thereover, said feeler means comprising a metal wire wiper for contacting the cards to be analyzed, a wiper holder for supporting said feeler means, pivot means associated with said wiper holder, guiding means stationarily mounted and defining a slot for guiding said pivot means, and cam means spaced from said pivot means and connected to said wiper holder, additional guiding means associated with said first guiding means in co-operation with said cam means and arranged during insertion of said wiper holder into operative position to force said feeler means into working position prior to enabling rotative movement of said wiper holder about the axis of said pivot means, said additional guiding means being arranged to allow removal of said pivot means from said slot when removing said feeler means from its working position.

9. A device for analyzing record cards comprising in combination, feeler means operable to engage and analyze said cards when moved thereover, said feeler means comprising a metal wire wiper for contacting the cards to be analyzed, a wiper holder for supporting said feeler means, pivot means associated with said wiper holder, guiding means stationarily mounted and defining a slot for guiding said pivot means, and latching means associated with said first-mentioned guiding means for locking said pivot means in that position in which only rotative movement of said wiper holder about the axis of said pivot means is possible.

10. For use in connection with analyzing apparatus for record cards, sensing means comprising a metal wire wiper, an arrangement comprising in combination, holding means for holding said wiper, guide means and cam means on said holding means, and supporting means detachably supporting and locating the said holding means by engagement with said guide means and cam means, the said supporting means including a guide track to receive said guide means and also including guiding means having two guide surfaces, said guide surfaces being adapted for co-operation with the said cam means associated with said holding means each in a different direction of movement of the said holding means to thereby force said holding means during insertion thereof into said supporting means to move along a path different from the path of removal of said holding means from said supporting means.

CORNELIS HENDRICUS STUIVENBERG.
